UNITED STATES PATENT OFFICE.

JOHN F. SCHAEFER, OF FINDLAY, OHIO, ASSIGNOR TO THE COOPER CORPORATION, OF CINCINNATI, OHIO, A CORPORATION OF DELAWARE.

DESIGN FOR A TIRE.

Application filed June 24, 1924. Serial No. 9,955. Term of patent 3½ years.

To all whom it may concern:

Be it known that I, JOHN F. SCHAEFER, a citizen of the United States, residing at Findlay, in the county of Hancock and State of Ohio, have invented a new, original, and ornamental Design for Tires, of which the following is a specification, reference being had to the accompanying drawing, forming a part thereof.

Figure 1 is a perspective view of a tire showing my new design.

Figure 2 is an enlarged plan view of a fragment of the tire shown in perspective Fig. 1, and Figure 3 is a cross section of the tire taken on line 3—3, Fig. 2.

I claim:

The ornamental design for a tire, as shown.

JOHN F. SCHAEFER.
